UNITED STATES PATENT OFFICE.

THOMAS B. JEFFERY AND LUTHER M. COTTLE, OF CHICAGO, ILLINOIS.

BICYCLE-BACKBONE-BENDING MACHINE.

SPECIFICATION forming part of Letters Patent No. 361,523, dated April 19, 1887.

Application filed June 21, 1886. Serial No. 205,768. (No model.)

To all whom it may concern:

Be it known that we, THOMAS B. JEFFERY and LUTHER M. COTTLE, citizens of the United States, residing at Chicago, in the county of Cook and State of Illinois, have invented certain new and useful Improvements in Bicycle-Backbone-Bending Machines, which are fully set forth in the following specification, reference being had to the accompanying drawings, forming a part thereof.

The purpose of this invention is to provide means for forming the backbones of bicycles by bending them in a curve conforming to the rim of the drive-wheel and in a plane at right angles to that of the two branches of the fork in which the rear or guide-wheel has its axle journaled, and to do this without danger of flattening or creasing the tubular metal of which the backbone is made. Secondly, its purpose is to securely hold the backbone in position while the head or neck piece may be joined thereto, and to provide means for holding the neck with its axis radial to the curve of the backbone while it is being joined thereto.

The machine may be secured upon a horizontal bed or against a vertical wall. We have represented it in the drawings in the former position, and Figure 1 is, therefore, a sectional plan of the machine with a bicycle-backbone and head fixed therein, certain minor parts being cut away, as by a plane at the line $x-x$ on Fig. 2, which is a sectional elevation of the devices for holding and setting the head and neck piece, the section being made at the line $y-y$ of Fig. 1, and the view taken in the direction of the arrow-head, pointing toward said line. Fig. 3 is a section through $y-y$ in Fig. 1, some parts, however, being shown in elevation. Fig. 4 is a detail elevation of the fork-holding end of the backbone-former with the fork in position. Fig. 5 is a vertical section through the line $v-v$ of Fig. 1.

A is the table to which the machine is secured. B is a rigid frame secured thereto, consisting of the radial arms B' B'' and the segment B^3 , which is the former about which the backbone M is bent. The three parts constitute a sectoral frame, and may be formed integral, though, for convenience in substituting different backbone-formers without de-

taching the entire frame from the table, the backbone-former B^3 is made in a separate piece and bolted to the radial arms, as illustrated. This backbone-former comprises two parts, B^{30} , which is an arc of a circle, and B^{31} , which extends substantially in the direction of a tangent to that arc at one end. Near the end of the part B^{31} it is provided with a vertical aperture, b^{31} , and recesses b^{310} b^{310} upon the upper and lower surfaces, and between this apertured and recessed end and the commencement of the curve B^{30} said portion B^{31} is recessed, as at B^{32} . This form adapts the portion B^{31} to receive the fork M' , the bosses or journal-boxes M^{10} upon the ends of the latter entering the recesses b^{310} and the recess B^{32} , allowing space for the swell m' at the head of the fork at its junction with the backbone proper, while the aperture b^{31} is adapted to receive a bolt, which may be inserted through the axial bearing in the fork and through said aperture to fix the backbone in place while being formed.

Rigid and preferably integral with the arms B' and B'' , and radial to the curved portion B^{30} , I provide the slotted rib or bar B^4 , whose slot b^4 in a direction radial to the curve B^{30} receives the sliding pivot c of the lever C , said pivot being adjustably secured in said slot at the center of the curve B^{30} , as hereinafter explained. To said lever, outside the backbone-former B^3 , is pivoted the lever C' , and the lever C is provided with a series of small pivot-holes, c' , to permit the lever C to be adjusted to different positions, according to the radius of the backbone-former B^3 as the latter is changed, as hereinafter explained. The end of the lever C' carries a roller or pulley, C^2 , which has a peripheral groove, c^2 , semicircular in cross-section, to fit the backbone M . The rim or outer edge of the curved portion B^{30} of the backbone-former has a similar semicircular groove, b^{30} , in which the backbone lies when bent around the curve.

95
D is an arm, which has rigid with it the pivot-stud c , which projects from the said arm both above and below, the lower end passing into the slot b^4 and the upper end receiving the arm C . Said arm D is rigid with and at the same time adjustable with reference to the frame B by means of the link D^5 , which is

bolted at one end to the frame B by means of the bolt b' , which also secures the arm B^{30} to the arm B' , and at the other end to the arm D by means of the bolt d' . Its rigidity with the frame B may be further increased by providing the pivot-stud c with a clamp-nut, c^{10} , on the lower end, whereby the arm D may be clamped to the frame B.

Approximately radial to the arm B^{30} , and sliding upon the arm D, is the carriage E. To the outer end of the arm D we pivot the lever D' and connect said lever with the carriage E by the link D^2 , so that by rocking the lever over its pivot the carriage will be caused to slide on the arm D. Upon the carriage E is mounted the secondary carriage E', which slides in the first carriage, E, transversely to the motion of said carriage E on the arm D, and effect such sliding movement, and for another purpose, hereinafter explained, we provide at the outer end of the carriage E the lug c' , in which is pivoted the lever E^2 , to which is connected the link E^3 , which in turn is connected at its inner end to the plunger F, which slides in the bearings f in the carriage E', and has the stop-pins f^1 and f^{10} , which engage said bearings f on opposite sides, and cause the lever to move the carriage E' in its bearings on the carriage E after a limited motion of the plunger in its said bearings f .

To the carriage E', near its inner end, is secured the frame G, for holding the head and neck piece H. Said frame comprises the L-shaped piece G', to which is secured rigidly the T-shaped piece G², and the connection between these parts, operating as one, and the carriage E' is effected by means of the bolt g , which operates as a pivot, and the bolt g' , which passes through the slot g^2 in the part G², and is adapted to be set tight to bind said frame to the carriage E'. To the part G² is secured the upright bracket G³, which overhangs the frame G, and from its outer end is suspended the lever G³⁰. The screw-shaft G⁴, journaled in the upright arm of the bracket G³, and stopped between collars g^4 , secured to it on both sides of said upright arm, is screwed through the depending lever G³⁰.

The T-shaped part G² has the tapered socket g^{20} , to receive the lower spindle, h , of the neck-piece H, and through the piece G', in line with the socket g^{20} , is inserted the socketed center pin, G²¹, having the tapered socket g^{21} , to receive the upper spindle, h' , of the neck-piece H. Near the outer end of the center pin, G²¹, it has an annular groove, G²², and the lower end of the lever G³⁰ is forked, to stride the center pin in said groove. The rotation of the screw-shaft G⁴ causes the pendant G³⁰ to move the center pin, G²¹, toward or from the socket g^{20} , the bearing of said shaft in the bracket G³ being sufficiently loose to permit such movement without cramping.

The plunger F extends inward beyond its bearings in the carriage E', under the bracket G³, and, being in the horizontal plane of the backbone-former B⁸ and in line substantially

tangent thereto at the termination of the said backbone-former, itself terminates in a position to bear against the head-piece H when the latter is placed in the frame G, as herein-after explained.

The mode of use of this machine is as follows: The backbone being first formed with its fork, but unbent, is secured to the backbone-former by placing its fork astride the piece B³¹, and securing it thereto by a bolt through the aperture b^{31} . The tubular portion which is to be bent, being heated, extends in the direction of the dotted straight outlines N 80 N and lies in the groove b^{30} of the backbone-former B³⁰. The lever C being swung on its pivot back to the commencement of the curve B³⁰, the lever C' is secured by a suitable pivot-bolt in one of the holes c' in the lever C and turned on said pivot to bring the roller against the outer surface of the backbone, which is thus held in the grooves of the backbone-former and the roller. While thus securely grasped, the pressure being applied to the lever C' from the rear—that is to say, in the direction of the arrow-head in Fig. 1—the roller is pressed more firmly against the backbone, and by the same pressure the lever C is swung on its pivot, carrying with it the lever C' and the roller C' around the curve B³⁰, bending the backbone in conformity thereto. The lever

may be swung back and forth several times around the curve until the backbone no longer tends to spring out from the former, but is permanently bent to the shape of the latter. The head-piece H is placed in its frame G, its spindles being inserted in their sockets, respectively, and therein securely held by the action of the screw-shaft G⁴, drawing said sockets together. The lever D' is next swung over its pivot to cause the carriage E to slide on the bar D until the head-piece H is brought into proper position radially to make junction with the backbone. The lever E² is next operated and the plunger F caused to advance against the head-piece H and to force it and its frame G and the carriage E' in a direction tangential to the curve of the backbone-former toward the end of the backbone. By means of the two levers D' and E², causing the two carriages E and E' to slide in directions transverse to each other, the head-piece may be brought accurately to any desired point in relation to the end of the backbone, and there firmly held until secured by brazing or riveting.

Inasmuch as the curve of the backbone depends on the size of the wheel which is to be used, it is necessary to change the backbone-former B³⁰ and set the lever C in the slotted bearing B⁴ according to the curve which it is desired to produce. Inasmuch, also, as the axes of the spindles of the head must be radial, or substantially so, to the curve of the backbone, the frame G is adapted to be adjusted to bring the sockets g^{20} and g^{21} in such radial line with reference to the curve of each backbone-former. This is done by means of the slot g^2

in the part G² of the frame G, which permits the inner end of said frame to be swung on the pivot-bolt g, and in order to accurately adjust it I provide the adjusting-screw g¹⁰, screwed horizontally into the side of the bearing f of the plunger F, and projecting forward against the end of said part G², and operating as a stop for the same. This screw, being operated by a key or wrench, forces the inner end of the frame G toward the backbone-former B³⁰ until the proper direction is given to the axis of the head-piece H, and the bolt g' is then set tight, thereby clamping the frame G rigidly in correct position.

15 When the former B³⁰ is changed, the bolts d' and b' and the nut c¹⁰ are loosened, and the arm D being adjusted to bring the stud c at the center of curvature of the new former which is to be attached to the frame, said bolts 20 and nut are again tightened, and rigidity of the arm D with the frame and former is secured.

We claim—

1. In combination with the backbone-former 25 and means, substantially as described, for securing one end of the backbone thereto, a lever, as C, pivoted at the center of the curved portion of the said former, a secondary lever, as C', adjustably connected to the lever C, and 30 the roller C², journaled on the second lever outside of the said former, substantially as set forth.

2. In combination with the rigid frame B, having the detachable backbone-former B³, 35 provided at one end with suitable means, substantially as described, for holding one end of the backbone, and a lever, as C, having its pivot radially adjustable with reference to the curved portion of the backbone-former, and a 40 roller adjustably connected to said lever outside said former, substantially as set forth.

3. In combination, substantially as set forth, the rigid frame having the curved former B³⁰ and the arm D, rigid with said frame and approximately radial to the curve of the former, 45 a carriage, as E, and means, substantially as

described, for holding and centering the head-piece thereon and for sliding the carriage on the arm D.

4. In combination with the backbone-former, 50 the frame for holding the head-piece and the sliding carriages which sustain it and the levers which actuate them, respectively, one radially and the other tangentially to the curve of the backbone-former, substantially as set 55 forth.

5. In combination with the frame having the detachable backbone-former, the frame G and means, substantially as described, for adjusting it radially and tangentially, said frame 60 pivoted at one end on its sustaining carriage and adjustably secured at the other end, whereby its direction may be varied to bring the axial line of its sockets radial to the curve of the backbone-former, substantially as set forth. 65

6. In combination with the backbone-former and the frame G, for holding the head-piece and its sliding supports, the plunger F, located and operated tangentially to the curve of the backbone-former, whereby pressure is applied 70 to the head-piece directly in a tangential line with the end of the backbone to which it is joined, substantially as set forth.

7. In combination, substantially as set forth, the carriage E, the carriage E', sliding thereon, 75 the plunger F, sliding through bearings in the carriage E' and provided with stops to engage the carriage and limit such motion, and the lever E², pivoted on the carriage E and connected to the plunger F, whereby the plunger 80 acquires a limited range of motion in the carriage E' and communicates motion to said carriage at such limits.

In testimony whereof we have hereunto set our hands, this 17th day of June, A. D. 1886, 85 in the presence of two witnesses, at Chicago, Illinois.

THOS. B. JEFFERY,
LUTHER M. COTTLE.
